Primary Examiner — Rosemary K Tarcza*Assistant Examiner* — Alison M Ofstun(74) *Attorney, Agent, or Firm* — Stetina Brunda Garred & Brucker(57) **CLAIM**

The ornamental design for a charging cradle, as shown and described.

DESCRIPTION

FIG. 1 is a front perspective view of a charging cradle showing our new design;

FIG. 2 is a top view thereof;

FIG. 3 is a left side view thereof;

FIG. 4 is a front view thereof;

FIG. 5 is a right side thereof; and,

FIG. 6 is a bottom view thereof.

The broken lines present in the figures are included for the purpose of illustrating portions of the article that form no part of the claimed design.

1 Claim, 2 Drawing Sheets(56)
